WELL CLEANER

Claude C. Taylor, Whittier, Calif.

Application November 27, 1933, Serial No. 699,883

26 Claims. (Cl. 166—20)

This invention relates to well cleaners for removing debris, rotary mud, or other impediments to flow from producing strata into an oil well, and in addition, and more particularly, to a means 5 for removing clogging obstructions, from the openings through perforated well casings, which casings are frequently employed in oil producing strata and are commonly known as well screens or strainers.

10 A principal object of the present invention is to provide a well cleaner which will, by a single stroke of a reciprocating pump, force fluid outwardly through one of a series of perforations of a screen or casing, while coincidentally drawing fluid through an adjoining series of such perforations, and which by successive changes of the 15 positions, with respect to the perforations to be cleaned, of a series of packers with which it is provided, will operate to successively force fluid both outwardly and inwardly through said 20 perforations, the latter of said operations resulting in drawing clogging detritus into the casing where it may be removed, instead of driving it outwardly where it may wholly or partially seal off producing strata, or may later return to obstruct 25 said openings.

Another object of said invention is to provide a device which may be anchored in any desired 30 position within a perforated well casing or screen, and which, after cleaning a series of perforations at such positions may be readily removed and locked in a new location for a repetition of the operation on a new series of perforations.

Other important objects are facility of placement and change of position for operation, economy of manufacture and of service, and both economy and efficiency of operation.

The art prior to my invention discloses means whereby a packer may be locked in position within 35 a perforated casing, and whereby another packer may be reciprocated with relation to the first, the result being to force the fluid within the casing to and fro through the casing perforations between packers with the hope that such to and fro movement may temporarily remove 40 obstructions in the perforations. Such means and method, however, are haphazard in that, among other things, no positive means are provided for, after loosening the detritus, of drawing 45 it into the casing for later removal.

Other devices of the prior art operate by relatively movable packers anchored within a well casing to draw the clogging obstructions into the casing, but do not sufficiently provide for a positive pressure outward through the perforations,

which is frequently necessary in stubborn cases, to remove.

The apparatus of my present invention, on the contrary, operates to secure a positive flow of fluid outward through one series of perforations 5 and at the same time an in-flow through an adjoining and preferably lower series of such openings, the latter action operating to draw into the casing through the lower series of perforations, (which have previously been subjected to a forced 10 out-flow of fluid) the loosened screen obstructions, where they may be readily removed by methods well known in the art.

I attain the objects and correct the prior art deficiencies above briefly described by the devices 15 illustrated in the accompanying drawing in which—

Fig. 1 is a sectional view of a well-casing screen, my invention, shown positioned within the casing screen, being illustrated partly in section and 20 partly in elevation;

Fig. 2 is a horizontal section on line 2—2 of Fig. 1;

Fig. 3 is a horizontal section on line 3—3 of Fig. 1;

Fig. 4 is a horizontal section on line 4—4 of Fig. 1;

Fig. 5 is a fragmentary view of the means of operating the fluid by-pass at the lower end of my invention.

Similar indicating letters and numerals refer to similar parts through the several views.

1 indicates a well screen in the form of a perforated casing; 2, well tubing, to which is rigidly attached a piston rod or stem 3, carrying at its lower end a piston 4. Stem 3 passes, at its lower end, through a common form of anchoring device, the specific construction of which, not being of the essence of the present invention need not be minutely described, nor in the drawing illustrated in detail. Said anchoring device, however, consists of a sleeve 5 on the upper end of which is rigidly secured a slip expander 6. Slidably surrounding the lower portion of said sleeve 5 is a collar 7 to which is attached a plurality of bowed springs 8, the centers of the bowed outer surface of which being adapted for frictional engagement with the inside walls of the casing in a well known conventional manner. Sleeve 9, to which the upper ends of said bowed springs 8 are attached, carries suitable linkage 10, at the upper ends of which are attached slips 11, which slips are rigidly held by dove-tailed grooves and tenons in sliding engagement with the sloping exterior of expander 6. An important part of said 50

conventional anchoring means is stud 12 extending radially from sleeve 5 and adapted for engagement by a bayonet slot 13 in collar 7.

The extension of well tubing 2, namely, stem 3, passes, at its upper end, slidably through the center of slip expander 6, and at its lower end extends through any common form of stuffing box, such as indicated at 14, in the closed bottom of sleeve 5.

10 Screw-threaded to the outside of the lower end of sleeve 5, and downwardly extending therefrom, is a cylinder 15 in which piston 4 is adapted to slidily reciprocate in the manner and for the purposes hereinafter described. 16 indicates 15 a cylindrical member surrounding cylinder 15, the space between said cylinders 15 and 16 forming an annular chamber 17.

Extending upwardly from the upper surface of piston 4 studs 18-18 are adapted to register 20 and fit into corresponding recesses 19-19 in the under side of the bottom closure plate of sleeve 5.

An extension 20 of reduced diameter is secured in any suitable manner to the lower end of cylindrical member 16 and carries screw-threaded to 25 its lower end a coupling collar 21 which is provided with an upwardly extending lug, for purposes to be described, as shown at 22. Supported on the upper surface of said coupler 21 and closely but rotatably fitting the outside of said extension 20 of cylinder 16 is a sleeve 23, to which is rigidly secured in any suitable manner, in spaced relationship with each other, a plurality of packers diagrammatically illustrated at 24, 25 and 26, it being understood that said packers 30 may be of any suitable conventional form.

A pair of ports 27 and 28 through extension 20 above and below the packers, respectively, are positioned in horizontal alignment with ports 29 and 30 through sleeve 23. Ports 27 and 29 and

40 ports 28 and 30, respectively, may be turned out of registry by rotation of extension 20 which is connected with the well tubing, sleeve 23 being prevented from rotation by the friction of the packers, carried by the sleeve, on the well screen.

45 When the device is initially placed in the well or when it is desired to move the packers to a new location, the ports are turned into registry to permit fluid from above or below to flow to the opposite side of the packers and equalize fluid 50 pressure. The upwardly extending lug 22 of coupling collar 21 is adapted to travel within a notch or cut away portion 22a in the lower end of sleeve 23 and is positioned to permit lug 22 to engage one end of the notch and prevent further

55 relative rotative movement between extension 20 and sleeve 23 when ports 27 and 29 are, respectively, in registry with ports 28 and 30.

Screw-threaded into coupling 21 is a short nipple 31 to the lower surface of which is secured 60 in any suitable manner a flapper valve 32 which is maintained in closed position by the tension of spring 33. Registering corresponding ports through sleeve 23 and extension 20 are shown at 34, the innermost of which ports, namely, that 65 extending through extension 20, being normally maintained in closed position against pressure from the inside of sleeve 23 by a leaf spring controlled valve 35.

Extending from the bottom closure plate of 70 cylinder 15 is a tube 36, which at its lower end extends into and through the wall of extension 20 as indicated at 37, and there registers with a port controlled by an outwardly opening spring leaf-controlled valve 38.

75 39 and 40 designate open ports in the upper

walls of cylinder 15. Near the bottom of cylinder 15 a port 41 is provided which is connected by a short tubing conduit 42 through the walls of cylinder member 16. An inwardly opening leaf spring valve 43 controls the opening through said 5 port 41.

The operation of the device is as follows:

With its slips locked in contracted position and suspended from the lower end of the well tubing 10 the device is lowered into a well until the packers 24, 25 and 26 reach a position opposite the series of perforations in the well screen desired to be cleaned. The well tubing is then turned slightly to the right, when the bowed springs on the anchoring device which frictionally engage 15 the inner wall of the well casing will not respond to the turning movement. The sleeve 5, however, being locked by engagement of studs 18-18 with recesses 19-19 in the bottom plate of said sleeve 5, will move with said well tubing and will carry 20 stud 12 to the limit of its lateral movement in bayonet slot 13 when a slight lowering of the well tubing will disengage said stud from said slot. Such lowering of the well tubing will also carry 25 the slip expander downwardly while slips 11, restrained by the frictional engagement of their attached bowed springs 8, with the bore of the casing will be wedged into locking engagement with said bore. Thus the complete assembly of the well cleaning device and its anchoring means 30 will be held against relative movement with respect to the casing, which will permit piston 4 by means of its rod 3 and well tubing 2 to be reciprocated within the range of movement allowed by the interior length of cylinder 15. 35

It will be noted that, during the lowering of the device into the well, ports 27 and 28 in extension 20 register with ports 29 and 30 in sleeve 23, thus maintaining an open by-pass to permit fluid in the well to pass from the space below to the 40 space above the series of packers 24, 25 and 26.

The turning of the tubing for unlocking the anchoring device as above described will also coincidentally partially rotate extension 20 within sleeve 23, said sleeve being restrained from following the turning movement of the tubing by the frictional engagement of the packers with the bore of the casing. Such relative movement of extension 20 and sleeve 23 will close ports 27, 28, 45 29 and 30.

With the device locked in relative immovable 50 position at a desired point in the perforated casing the piston 4 is then alternately raised and lowered with a pumping stroke. As it is lowered fluid below it will pass out between packers 24 and 25, the movement of said fluid outwardly 55 forcing valve 38 open against the tension of its leaf spring, during which downward movement of said piston 4 valve 43 in the bottom of the cylinder 15 will remain closed.

The downward movement of said piston 4 will 60 also create a suction above said piston which will draw fluid through ports 34, passing valve 35, into extension 20, and upward through annular space 17, through ports 39 and 40, and into the 65 upper portion of said cylinder 15.

On the upward stroke of piston 4 fluid will be drawn through conduit 42 past valve 43 and into the lower portion of cylinder 15. The upward stroke of the piston will also force fluid above the 70 piston outward through ports 39 and 40, downward through annular space 17 and through extension 20, and outward through valve 32.

It will thus be seen that as the piston moves 75 downwardly fluid will be forced outwardly

through the perforations in the screen between the packers 24 and 25, and during the same movement fluid will be drawn inwardly through the perforations between packers 25 and 26.

It will be noted that in the accompanying drawing little regard has been paid to proportions of the different parts, the illustrations being largely diagrammatical and illustrative; and it is quite obvious also that details of construction and assembly of the various parts may be changed and that various modifications in means for securing the double action of the piston, of alternately or coincidentally forcing fluid outwardly through one series of well perforations and inwardly through another may readily be devised by those of skill in this art, without departing from the essence of my invention.

What I claim and desire to cover by Letters Patent is:

- 0 1. In a well cleaner, the combination of a plurality of packers concentrically mounted in spaced relation with each other, a tubular support for said packers, anchoring means to removably lock said packer-support at a selected position within a well, a cylinder, a piston adapted to be reciprocated within said cylinder, a conduit from one end of said cylinder to a space between two of said packers, a valve controlling said conduit against inward flow, a conduit from the other end of said cylinder to a space between one of the last mentioned packers and another, a valve controlling said last mentioned conduit against outward flow, and means to reciprocate said piston. 20
- 15 2. In a well cleaner, the combination of a plurality of packers concentrically mounted in spaced relation with each other, a tubular support for said packers, anchoring means to removably lock said packer-support at a selected position within a well, a cylinder, a piston adapted to be reciprocated within said cylinder, a conduit from one end of said cylinder to a space between two of said packers, a valve controlling said conduit against inward flow, a conduit from the other end of said cylinder to a space between one of the last mentioned packers and another, a valve controlling said last mentioned conduit against outward flow, a by-pass from a point below the lowermost to a point above the uppermost of said packers, and valve means to close said by-pass when said packers are anchored in operative position within the casing and means to reciprocate said piston. 40
- 30 3. In a well cleaner, a combination of a plurality of packers concentrically mounted in spaced relation with each other, a tubular support for said packers, anchoring means to removably lock said packer-support at a selected position within a well, a cylinder, a piston adapted to be reciprocated within said cylinder, a conduit from one end of said cylinder to a space between two of said packers, a valve controlling said conduit against inward flow, a conduit from said last mentioned end of said cylinder to a point within a well casing on one side of said plurality of packers, a valve controlling said conduit against outward flow from said cylinder, a conduit from the other end of said cylinder to a space between another pair of said packers, a valve controlling said last mentioned conduit against outward flow, and means to reciprocate said piston. 50
- 35 4. In a well cleaner, a combination of a plurality of packers concentrically mounted in spaced relation with each other, a tubular support for said packers, anchoring means to removably lock said packer-support at a selected position within a well, a cylinder, a piston adapted to be reciprocated within said cylinder, a conduit from one end of said cylinder to a space between two of said packers, a valve controlling said conduit against inward flow, a conduit from the other end of said cylinder to a point within a well casing on one side of said plurality of packers, a valve controlling said conduit against outward flow from said cylinder, a conduit from the other end of said cylinder to a space between another pair of said packers, a valve controlling said last mentioned conduit against outward flow, and means to reciprocate said piston. 60
- 40 5. In a device of the character described, a plurality of well-casing packers concentrically connected in spaced relation with each other, means to anchor said packers at a selected zone within a well screen, a cylinder concentrically positioned in spaced relation to said packers, a piston closely and slidably fitting said cylinder and adapted to be reciprocated to and fro with relation to the position of said packers, means adapted to communicate pressure from within one end of said cylinder to a space between an adjoining pair of said packers, said means also operating to prevent suction in said space from said last mentioned end of said cylinder, means adapted to communicate suction from the other end of said cylinder to a space between another pair of adjoining packers, said means also operating to prevent pressure in said space from said last mentioned end of said cylinder, and means to reciprocate said piston. 70
- 45 6. In a device of the character described, a plurality of well-casing packers concentrically connected in spaced relation with each other, means to anchor said packers at a selected zone within a well screen, a cylinder concentrically positioned in spaced relation to said packers, a piston closely and slidably fitting said cylinder and adapted to be reciprocated to and fro with relation to the position of said packers, means adapted to communicate pressure from within one end of said cylinder to a space between an adjoining pair of said packers, said means also operating to prevent suction in said space from said last mentioned end of said cylinder, means operated by said last mentioned suction to permit fluid on one side of said plurality of packers to be drawn into said last mentioned end of said cylinder, means adapted to communicate suction from the other end of said cylinder to a space between another pair of adjoining packers, said means also operating to prevent pressure in said space from said last mentioned end of said cylinder, means to relieve pressure in said last mentioned end to said cylinder, and means to reciprocate said piston. 80
- 50 7. In a device of the character described, a plurality of packers mounted in spaced relation with each other, means to anchor said packers at a selected zone within a well screen, a cylinder mounted adjacent to and concentric with said packers, a piston adapted to be reciprocated within said cylinder, means to control alternate pressure and suction from one end of said cylinder so as to apply said pressure to the series of well screen perforations between two of said packers 75

- and to prevent application of said suction to said last mentioned series of screen perforations, and means to control alternate pressure and suction from the other end of said cylinder so as to apply suction to a series of well screen perforations between one of first above mentioned packers and another and to prevent application of said pressure to said last mentioned series of screen perforations.
10. 8. In a device of the character described, a plurality of packers spaced apart, a cylinder, a piston reciprocating with said cylinder, conduits from the top and bottom of said cylinder, respectively, to spaces between different pairs of said packers and valvular means adapted to close one of said conduits to suction, and another of said conduits to pressure from said cylinder.
9. In a well cleaner a plurality of packers immovable with relation to each other, a pump to create fluid pressure, means to communicate said pressure to the space between one pair of said packers and means to convey fluid from between a second pair of packers to below the lowermost packer.
10. 10. In a well cleaner, a pair of packers immovable with relation to each other, a cylinder, a piston adapted to reciprocate in said cylinder, a one way conduit from a space between said packers to one end of said cylinder and a conduit from the opposite end of said cylinder to a point below the lower packer.
11. In a device of the character described, a plurality of packers, a cylinder, a piston adapted to reciprocate within said cylinder, conduits to utilize pressure caused by such reciprocation to force fluid between one pair of packers, and means to convey fluid from between a second pair of packers to a point below the lowermost packer.
12. In a well cleaner, a plurality of packers immovable with relation to each other, a pump to create a partial vacuum and pressure, means to communicate the vacuum created by said pump to a space between two of said packers, and means to communicate the pressure in said pump to a space between another pair of said packers.
13. In a device for cleaning perforations of a well-casing-screen, a tubular member, a pump connected to said tubular member, a sleeve on said tubular member, a packer on said sleeve adapted for frictional contact with the casing-screen to resist rotation of said sleeve, a pair of packers connected to said tubular member substantially concentric with said first-mentioned packer, means to communicate the pressure created by said pump with the zone between two of said packers, means to communicate the suction created by said pump with the zone between another pair of said packers, and ports in said sleeve and tubular member on opposite sides of said packers, adapted to be brought into registry by rotation of said tubular member.
14. In a well cleaner, a casing, a tubular member within said casing, a pump connected to and actuated by said tubular member, a sleeve rotatably mounted on said member, a packer secured to said sleeve adapted to frictionally engage said casing so as to resist rotative movement relative theretween, a second packer connected to said tubular member, means to communicate suction of said pump with the zone between said packers, and ports in said tubular member adapted to be brought into registry with respective ports in said sleeve by rotation of said member.
15. In a well cleaner, a cylinder, a plurality of packers immovable with relation to each other connected to said cylinder, a piston adapted to be reciprocated within said cylinder to simultaneously create suction and pressure therein, means to communicate suction in said cylinder with the space between two of said packers, and means to communicate pressure created within said cylinder with the space between another pair of said packers.
16. In a device of the character described, a stem, a pump connected to and actuated by reciprocation of said stem, a plurality of packers connected to said pump, and means to communicate suction and pressure created by actuation of the pump to respective zones between different pairs of said packers on the downward movement of said stem.
17. In a well cleaner, a stem adapted for reciprocation, a pump connected to and actuated by reciprocation of said stem, a pair of packers connected to said pump, means to communicate suction from said pump to the area between said packers, and means to convey fluid drawn from between said packers by said pump to the zone below the lowermost packer.
18. In a well cleaner, a pump comprising a working barrel and a plunger disposed within said barrel, a stem connected to said pump adapted by its reciprocation to relatively reciprocate the barrel and plunger, a pair of packers connected to said pump, a passage to communicate suction created in said barrel with the zone between said packers, and valvular means controlling said passage adapted to open at the beginning of the downward movement of the stem but close during the opposite stroke of said stem.
19. In a well cleaner, a pump comprising a working barrel and a plunger disposed within said barrel, a stem connected to said pump adapted by its reciprocation to relatively reciprocate the barrel and plunger, a pair of packers connected to said pump, a passage to communicate suction, at the beginning of the downward movement of said stem, created in said barrel by movement of the plunger with respect to said barrel with the zone between said packers.
20. In a well cleaner, a pump comprising a working barrel and a plunger disposed within said barrel, a stem connected to said pump adapted by its reciprocation to relatively reciprocate the barrel and plunger, a pair of packers connected to said pump, and communicating means between said pump and the zone between said packers throughout the downward suction stroke of said pump.
21. In a well cleaner, a stem, a pump connected to said stem and adapted to be actuated by reciprocation thereof to create suction, a pair of packers spaced apart and connected to said pump, and means to communicate a steady suction created by said pump with the zone between said packers throughout the downward suction stroke of said pump.
22. In a device for cleaning perforations of a casing, a tubular member, a pump connected to said tubular member, a sleeve on said tubular member, a packer between and engaging the casing and sleeve to resist relative rotation therebetween, a second packer on said sleeve, said member and sleeve having a pair of ports above and below said packers, respectively, the ports of said member and said sleeve being adapted to be moved in and out of registry by rotation of said tubular member.
23. In a well cleaner, a working barrel, a piston

reciprocably disposed within said barrel, means connected to said piston to cause by its reciprocation the reciprocation of said piston with respect to said barrel, a pair of packers, means to connect said packers to said barrel, and communicating means between said barrel and the zone between said packers throughout the downward stroke of said means.

24. In a device of the character described, a tubing string, a working barrel, a piston within said working barrel, means to connect said piston to said tubing string so as to reciprocate said piston with respect to said barrel by reciprocation of said tubing, a pair of packers, means to connect said packers to said working barrel in spaced relation with respect to each other, and means to communicate suction created in said working barrel on the downward movement of said tubing string with the zone between said packers throughout the downward stroke of said tubing.

25. In a well cleaner, a pump comprising a working barrel, and a piston disposed reciproca-

bly within said working barrel, means connected to said piston to cause by its reciprocation the actuation of said pump, a pair of packers, means to connect said packers to said barrel, and communicating means from the zone between said packers to said pump and from said pump to below said lowermost packer, whereby fluid is drawn from between the packers by actuation of the pump and discharged below the lowermost packer.

26. In a device of the character described, a tubing string, a working barrel, a piston within said working barrel, means connecting said piston with said tubing string, a pair of packers, means to connect said packers to said working barrel, communicating means from the zone between said packers to said pump and from said pump to below the lowermost packer, whereby fluid is drawn from between the packers by actuation of the pump and discharged below the lowermost packer.
